(57) **CLAIM**

The ornamental design for a pod shape container, as shown and described.

DESCRIPTION

FIG. 1 is a perspective view of a pod shape container showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, shown in an open position.

The broken lines in FIG. 8 illustrate the environment of the claimed design and form no part thereof.
